Primary Examiner — Catherine R Oliver-Garcia

CLAIM

The ornamental design for a baton, as shown.

DESCRIPTION

FIG. 1 is a perspective view of a baton showing my new design.

FIG. 2 is a left elevation view of the baton of FIG. 1.

FIG. 3 is a right elevation view of the baton of FIG. 1.

FIG. 4 is a front elevation view of the baton of FIG. 1.

FIG. 5 is a rear elevation view of the baton of FIG. 1.

FIG. 6 is a bottom plan view of the baton of FIG. 1; and, FIG. 7 is a top plan view of the baton of FIG. 1.

The broken lines depict portions of the baton that form no part of the claimed design.

1 Claim, 5 Drawing Sheets

US D802,706 S
